(57) **CLAIM**

The ornamental design for a remote control accessory for an earth ground tester, as shown and described.

DESCRIPTION

FIG. 1 is an upper front right perspective view of a remote control accessory for an earth ground tester showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left elevation view thereof; and,

FIG. 7 is a right elevation view thereof.

The broken lines of FIGS. 1-7 illustrate environmental subject matter and form no part of the claimed design.
